BABY WALKER

Marcel O. De Vos, Grosse Pointe Woods, Mich., assignor to Grow-Rite Corporation, a corporation of New York

Filed Dec. 27, 1961, Ser. No. 68,092

Term of patent 14 years

(Cl. D15—1)

I claim:

The ornamental design for a baby walker, substantially as shown.
